Charles R. Seale.

UNITED STATES PATENT OFFICE.

STEPHEN L. MORGAN, OF SKANEATELES, NEW YORK.

LOCK FOR MOTOR-VEHICLES.

1,277,992.

Specification of Letters Patent. Patented Sept. 3, 1918.

Application filed June 4, 1917. Serial No. 172,588.

To all whom it may concern:

Be it known that I, STEPHEN L. MORGAN, a citizen of the United States, residing at Skaneateles, in the county of Onondaga and State of New York, have invented a certain new and useful Improvement in Locks for Motor-Vehicles, of which the following is a specification.

The invention relates to devices for locking the mechanism of an automobile or analogous motor vehicle so that such vehicle cannot be operated until such mechanism is again released, and the object of the invention is to provide a simple, efficient and easily operated locking device for thus preventing the theft or unauthorized use of the car, and a further object is to provide such locking device in such relation to the gear shift lever of the selective type as to hold such lever in the neutral position in which the rotation of the motor is idle and the car cannot be started or run under its own power.

A further object is to apply such locking means to such lever with provisions for engaging or disengaging the fixed socket in which such lever is mounted, and a further object is to provide a locking mechanism of the combination type which may be easily set to any desired sequence of letters or numbers within the range of the lock mechanism.

The invention consists in certain novel features, and details of construction and arrangement by which the above objects are attained, to be hereinafter described and claimed.

The accompanying drawings form a part of this specification and show approved forms of the invention.

Figure 1 is a front elevation, partly in vertical section, showing a preferred form of the invention designed to encircle the shift lever and slide concentrically thereon in locking and releasing.

Fig. 2 is a corresponding side elevation, partly in vertical section.

Fig. 3 is a vertical section through the locking mechanism, on a larger scale, the portion of the lever being shown in elevation.

Fig. 4 is a corresponding top or plan view.

Fig. 5 is an elevation of a portion of the lever, with the locking disks in section, showing the relation of the disks thereto.

Fig. 6 is a horizontal section, partly in plan view, taken on the line 6—6 in Fig. 3.

Fig. 7 is a plan view of the under face of the lock, corresponding to Fig. 3, and with the lever in horizontal section.

Fig. 8 is an edge view of one of the locking disks and its adjustable lug.

Fig. 9 is a corresponding plan view.

Fig. 10 is a diametrical section taken on the line 10—10 in Fig. 9, and partly in elevation.

Fig. 11 is a side view of one of the lugs alone.

Similar letters of reference indicate like parts in all the figures.

A is the gear shift lever, B the ball or spherical fulcrum thereof mounted in a socket C and having a downward extension A⁴ through which the speed changes are initiated as usual. D is a vertical flange or rim on the socket C forming an annular recess around the lever in which the latter is oscillated in the various directions required in making the speed changes, and in which the lever occupies the central position when in "neutral". Such recesses in varying forms are usually present in cars of this class of the selective type, and in this form of the invention the recess is utilized in holding the lever in neutral by inserting in such recess a filling-piece preferably an annulus mounted to slide vertically on the lever and fitting closely within the recess when in the lowered position. It is obvious that if such boss or annulus be thus inserted and locked the lever must remain in neutral until the annulus is again removed and the lever thus released.

The insertion of the filling-piece or boss and the means for retaining it in locked relation in the recess may be varied according to varying conditions; in the form of the invention shown in the figures above referred to the lever A has a ridge or feather A¹ extending longitudinally for a short distance above the socket C, in which are spaced notches a, a¹, a². A sleeve E slotted longitudinally to match to the feather A¹ incloses the lower portion of the lever and is mounted to slide thereon with the outer margin of the feather protruding through the slot. The lower end of the sleeve is inclosed in a collar E¹, also slotted at e to match to the

projecting edge of the feather A¹, and has a flange carrying on its under face an annulus or circular boss E² adapted to match to the recess in the socket C when the lever A is in the central position and the collar lowered therein.

F¹, F², F³ are circular locking disks arranged one above the other, separated by spacing rings G, and encircling the lever A and sleeve E, and in the lowered and locked condition each disk coincides with one of the notches a, a¹, a² and may be rotated on the sleeve while thus engaged each in its notch. The central hole in each disk has a notch f which when brought into coincidence with the feather by the rotation of the disk, matches to the protruding edge thereof, and when all the disks are thus rotated to bring all the notches f in line with each other and with the feather they may all slide longitudinally of the lever together with their spacing rings and connected collar, and the boss E² thus raised sufficiently to disengage the recess and permit the lever to be moved from neutral and perform its usual functions.

Each locking disk has a peripheral flange F⁴ cut away at one point as at f¹ to admit a block or lug F⁵ shaped to match to the flange F⁴ and inclose the latter with a portion of the disk, and may be slid thereon and located at any desired point in the periphery of the disk and held by a setscrew F⁶. The lugs project above the disks and the one on the lowermost disk F³ lies in the path of a downwardly projecting pin F⁷ on the next disk F² above, the lug of which is similarly located relatively to a pin on the uppermost disk F¹, the lug F⁵ on the latter lies in the path of a pin H² on a ring H¹ forming a portion of the casing H in which the locking disks and spacing rings are inclosed and which is rotatively mounted relatively thereto and to the sleeve and lever. The uppermost spacing ring G has a flange G¹ serving with the ring H¹ to close the upper end of the casing H and carries a fixed mark G² adapted to serve with letters, numerals or other marks on the upper face of the rotatable casing in correspondingly moving the locking disks.

Thus by turning the casing in one direction, to the left for example, a sufficient number of times, approximately three times in the lock as shown, until all the pins lie in contact with their lugs, the lowermost disk F³ is located to unlock by turning the casing to the right approximately three times, stopping at the last turn with the first number of the combination selected presented at the mark G² in which position the lowermost disk will have been turned to bring its notch f into coincidence with the feather and will be held in such position by friction. Approximately two turns to

the left and stopping with the selected number for the second disk at the fixed mark G² brings the notch of the second disk F² in line with the feather, and then on turning the casing approximately one turn to the right to bring the number of the first disk F¹ to the mark, all the notches f will match to the notches in the spacing rings and to the feather and permit the whole to be raised and the lever released. To set the disks to the desired combination of numbers, the casing H is loosened and raised to expose the disks and the setscrews F⁶ are slackened to permit the lugs F⁵ to be moved on their disks and again secured in the positions at which the notches f will coincide with the feather when the desired numbers are presented in proper sequence to the mark G² as above indicated, the casing H is then lowered and secured.

In order to hold the collar and its boss in the elevated position a spring latch L is provided arranged to enter and engage in a hole a³ in the gear shift lever and support the whole until again withdrawn. While thus elevated the notches f are all in engagement with the feather and the disks held against rotation. On withdrawing the latch the casing will descend and the lever being in the central position the boss E² will again enter the recess in the socket C and hold the lever in this central or neutral position. The disks F¹, F², F³ will then lie on the same level as and in coincidence with the notches a, a¹, a² in the feather and by rotating the casing in either direction one or more of the notches f will be moved out of line thus engaging one or more of the disks in the feather-notches and the lever will be locked until the several numbers of the combination are again brought successively to the mark G² as before indicated.

To avoid the danger of one of the disks accidentally engaging one of the notches a, a¹, a² other than its own in the act of lowering the collar, the notches are made successively wider and the disks successively thicker, see Fig. 5, by which arrangement the lower disks cannot enter the upper notches.

The lugs may be placed at any desired points on the disks and the combinations thus varied indefinitely, so that a car owner may set the lock to any combination of three numbers he may select and may change the combination as often as desired.

The feather may be a permanent fixture on the lever or may be attached thereto by screws; if the latter the screws are so spaced as to insure that one or more shall lie concealed by the casing and collar in all positions.

I claim:—

In a locking device of the character set forth, a series of annular locking disks each

having a peripheral flange with an opening therein, a lug arranged to engage said flange and circumferentially adjustable thereon and to be admitted through such opening, and means for holding said lug in a selected position on said flange.

5 In testimony that I claim the invention

above set forth I affix my signature, in presence of two witnesses.

STEPHEN L. MORGAN.
